UNITED STATES PATENT OFFICE.

ROBERT J. ORR, OF NEW YORK, N. Y., ASSIGNOR TO UNDERWOOD TYPEWRITER COMPANY, OF NEW YORK, N. Y., A CORPORATION OF NEW JERSEY.

TYPE-WRITING MACHINE.

No. 890,372.

Specification of Letters Patent.

Patented June 9, 1908.

Application filed June 22, 1907. Serial No. 380,196.

To all whom it may concern:

Be it known that I, ROBERT J. ORR, a citizen of the United States, residing in New York city, borough of Manhattan, in the county of New York and State of New York, have invented certain new and useful Improvements in Type-Writing Machines, of which the following is a specification.

This invention relates to typewriting machines, and particularly to means for gaging and alining the side edge of the sheet of paper as it is being introduced into the machine and passed forwardly around the platen.

One of the principal objects of the invention is to facilitate the adjustment of said side gages or guides, as well as the front paper-guiding fingers, to accommodate different widths of sheets to be used.

In carrying out this feature of invention, I couple the side guide directly to the front guiding finger, so that both may be adjusted together along the platen, and so that when either one is adjusted to the right position, the other is necessarily adjusted to a corresponding position.

The front paper guiding fingers of the well known "Underwood" typewriting machine are mounted by means of brackets upon a rod extending along the platen at the rear thereof, and are independently swiveled on said rod so as to be turned up away from the platen. In carrying out my invention, I mount the side guides on the same rod, and couple them to the front guiding fingers, (or to the brackets that carry said fingers), so that the adjustment of either the finger or the side guide which is coupled thereto, insures a corresponding adjustment of the other of the coupled member.

In the accompanying drawings, Figure 1 is a plan view of the platen frame of the Underwood typewriting machine showing my improvements applied thereto. Fig. 2 is a perspective fragmentary view of a typewriter platen and paper table, showing the improved paper-guiding device. Fig. 3 is an end view, showing the parts in normal positions. Fig. 4 is a view similar to Fig. 3 but showing the paper-guiding finger raised from the platen. Figs. 5 and 6 are plan and side elevations, respectively, of the improved side guide. Figs. 7 and 8 are a side view and plan, respectively, of the paper-guiding finger and the bracket therefor.

The usual platen 1 is journaled in a frame

2 having an inclined paper table 3. The ends 2 of the platen frame are connected by a fixed rod 4, having on its under side a longitudinal groove or key-way 4^a. Swiveled on said rod 4 and extending forwardly therefrom is a bracket 5, the forward end of which is bent at right angles, to form an ear 6. To this ear is attached a springy finger 7, curved forwardly and down around the front of the platen, for guiding the paper and pressing the same against the platen. Carried on said paper-guiding finger is the usual pressure roller 8. From the bracket 5 a bar 9 extends along rod 4, and is bent up to form an ear 10; said rod 4 passing through both said ear and the rear end of the bracket 5. The usual roll or lever 12 is pressed by a bowed spring 11 into said key-way 4^a, thereby pressing the roll 8 against the platen.

Mounted against rotation on the rod 4 and extending rearwardly therefrom, is an arm 15 for guiding the paper at its side edge, said arm carrying at its rear end an inclined paper-supporting flange 16, which lies close to the surface of the inclined paper table 3, the inclination of said flange agreeing substantially with the inclination of the paper table, and the side guide and flange just clearing said table. A key 17 on arm 15 fits in the key-way 4^a in the rod 4, to prevent the arm from turning. Although the arm 15 and bracket 5 are coupled together, still rotation of the bracket on the rod 4 independently of the arm 15, is permitted. I provide the arm 15 with a curved slot or slots 18, to receive the shank of screws 20 each having a nut 21, the flat edge of the nut engaging the rod 4, to prevent the nut from turning. The screws are tapped into holes 19 in the brackets 5.

The arm 15 is slightly offset as at 22, where it is coupled to the bracket 5, so as to aline with said bracket, Fig. 1, and thereby facilitate the alining of the side edge of the paper in the machine. The limits of the adjustment of the guide and bracket along the rod 4, are determined by collars 23.

In Fig. 3 the bracket 5 is shown in its lowermost position, with the roller 8 of the paper-guiding finger 7 in normal position on the platen, and in Fig. 5 the same parts are shown, but with the paper-guiding finger released or swung up away from the platen.

Having thus described my invention, I claim:

1. In a typewriting machine, the combina- 110

- 2
5. In a typewriting machine, the combination of a platen, a platen frame, a rod fixed in the platen frame above the platen, an arm mounted on said rod against rotation and extending rearwardly therefrom to support and guide the paper at its side edge, and a paper guiding finger rotatable on said rod and extending forwardly therefrom and curving down around the front of the platen; said arm and finger being coupled together for simultaneous adjustment along said rod.
10. 2. In a typewriting machine, the combination with a platen frame and a rod fixed in said platen frame, of a spring-pressed paper-guiding finger journaled upon said rod and extending forwardly therefrom, a side guide mounted upon said rod and extending rearwardly therefrom and having a spur or key to fit a key-way in said rod to prevent rotation of the side guide on the rod, and also having a curved slot, and means engaging the curved slot to couple the side guide and the paper-guiding finger together, the paper-guiding finger being rotatable on the rod, and said paper-guiding finger and said side guide being adjustable together along said rod.
15. 3. In a typewriting machine, the combination with a platen, a platen frame, and a rod fixed in said platen frame, of a bracket swiveled on said rod, a paper-guiding finger attached to said bracket and extending forwardly, the bracket at its point of attachment to the paper-guiding finger being offset to approximately the width of the finger, an arm also mounted upon said rod and extending rearwardly therefrom, said arm having a paper-supporting flange at its rear end, and also having a spur or key fitting the key-way in said rod to prevent rotation of said guide thereon, and a curved slot formed in said arm, means extending through said slot for coupling the arm to the bracket, said slot permitting the rotation of the bracket on the rod independently of the arm, and the arm and bracket being adjustable together along the rod; said arm being offset at its point of coupling with the bracket so as to align with said bracket.
20. 4. In a typewriting machine, the combination with a platen, and a platen frame, of a rod mounted upon said platen frame and extending along the upper rear side of the platen, an arm mounted upon said rod and extending backwardly for guiding the side edge of the paper, said arm being adjustable along the rod, and a paper guiding finger pivotally connected to said arm, and extending forwardly and downwardly from the pivot around the front of the platen, the finger being movable about its pivot upwardly from the platen, and the finger and arm being adjustable together along the rod; a spring being provided for pressing the finger towards the platen.
25. 5. In a typewriting machine, the combination with a platen, and a platen frame, of a rod mounted upon said platen frame and extending along the upper rear side of the platen, an arm mounted upon said rod and extending backwardly for guiding the side edge of the paper, said arm being adjustable along the rod, and a paper guiding finger pivotally connected to said arm, and extending forwardly and downwardly from the pivot around the front of the platen, the finger being movable about its pivot upwardly from the platen, and the finger and arm being adjustable together along the rod; a spring being provided for pressing the finger towards the platen.
